United States Patent

Des. 239,789
Patented May 11, 1976

239,789

PEDIATRIC CRIB

Stuart N. Mann, Derby, N.Y., assignor to
John F. Hurley, Scituate, Mass.

Filed Oct. 31, 1974, Ser. No. 519,411

Term of patent 14 years

Int. Cl. D6—01

U.S. Cl. D6—16

Fig. 2.

Fig. 1.

FIG. 4.

FIG. 3.

FIG. 1 is a perspective view of a pediatric crib showing my new design;

FIG. 2 is a top plan view thereof;

FIG. 3 is a side elevational view thereof, both sides being identical; and

FIG. 4 is an end elevational view thereof, both ends being identical.

I claim:

The ornamental design for a pediatric crib, as shown and described.
